UNITED STATES PATENT OFFICE.

CHARLES W. GUMBES, JR., OF PHILADELPHIA, PENNSYLVANIA.

SIGNAL.

SPECIFICATION forming part of Letters Patent No. 626,903, dated June 13, 1899.

Application filed April 15, 1897. Serial No. 632,254. (No model.)

To all whom it may concern:

Be it known that I, CHARLES W. GUMBES, Jr., a citizen of the United States, residing at Philadelphia, in the county of Philadelphia 5 and State of Pennsylvania, have invented certain new and useful Improvements in Signals; and I do hereby declare the following to be a full, clear, and exact description of the invention, such as will enable others skilled in the art to which it appertains to make and use the same.

This invention relates to railway-signals; and the object in view is to provide a simple and effective audible signal adapted to be used adjacent to tunnels and bridges over the road-bed for the purpose of warning the brakemen and others upon the tops of cars of the near approach of the train to said tunnel or bridge, thus avoiding serious accident, 20 which might otherwise result. The improved safety device is intended to be used either in connection with the ordinary pending ropes or wires in common use or independently thereof, as may be desired.

To this end the invention consists in certain novel features and details of construction and arrangements of parts, as hereinafter fully described, illustrated in the drawings, and incorporated in the claims hereto appended.

In the accompanying drawings, Figure 1 is a perspective view of a section of the railway, showing the improved signal and the operating mechanism therefor located adjacent to a bridge. Fig. 2 is an enlarged detail view showing the trip for sounding the signal and the means for retracting said trip. Fig. 3 is a sectional view of the audible signal. Fig. 4 is a similar view of the signal, showing modified means for actuating the hammer or clapper. Fig. 5 is a detail side elevation of the shaft and trip-arm and spring. Fig. 6 is a detail cross-section through the same.

Similar numerals designate corresponding parts in the several figures of the drawings.

Referring to the drawings, 1 designates a section of the railway, and 2 a bridge constructed thereover. For the purpose of carrying out the present invention a post or standard 3 is erected at one side of the road-bed and preferably of a height sufficient to

bring an audible alarm in the shape of a gong 4 upon the approximately horizontal plane of the tops of the cars, thus enabling said gong to be readily heard by persons thereon. This 55 gong is shown to consist of a bell 5, secured upon a post 6, projecting laterally from the main post or standard 3.

7 designates the clapper or hammer, which is mounted on the free end of a spring or resilient arm 8, which is attached at its opposite end to the post or standard 3. Connected to the hammer 7 or arm 8 is a cord, wire, or other flexible connection 9, which runs around a pulley 10 on the standard 3, thence downward in parallel relation to said standard, and upon reaching the ground passes around another pulley 11, whence said connection extends transversely of the road-bed and beneath one of the rails. At a suitable point 70 between the rails is arranged a third pulley 12, beneath which the connection 9 runs. The connection 9 then extends upward and is attached fixedly at the point 13 to a trip-arm 14 on a shaft 15. 75

The shaft 15 is located between the rails of the track and is mounted in suitable bearings 16 at its ends, the trip-arm 14 being located intermediate the ends of the rock-shaft. Surrounding the shaft is a coiled spring 17, which 80 is so arranged as to exert its tension or torsional action upon the trip-arm 14 for restoring said arm to a substantially vertical position, such being the normal position of said arm. The arm 14, which is a continuation or 85 extension of the spring, extends upward sufficiently to contact with and be thrown downwardly by the various axles of the train passing thereover, so that said trip-arm will be thrown downward and the gong will be sounded 90 at least twice for every car that passes over the trip mechanism, thus warning persons on the top of each car of approaching danger. The heel end 18 of the spring is bent at an angle and extended through a transversely-flared mortise 19 in the shaft 15, so that as the train backs away from a tunnel or bridge the arm 14 may not only spring or yield backward, but the spring 17 itself may turn backward around the shaft 15, thus allowing the axles to pass over the arm without sounding the alarm. 95 100

Instead of mounting the hammer 7 on a resilient arm or spring 8 said hammer may be arranged on one end of a plunger 18, mounted to slide in suitable bearings 20 on the stand-
ard 3, the said plunger being actuated by means of a spring 21, coiled around the same. In this construction the connection 9 may be attached to the heel end of the plunger and the plunger will be drawn backward against the tension of the spring when the trip-arm 14 is thrown downward. Under either construction as the axle passes off the trip-arm 14 the spring 17 by its torsional action will quickly restore said arm to its normal position, thus allowing the spring 8 or 21, as the case may be, to throw the bell-hammer forcibly and quickly against the bell 5.

Having thus described the invention, what is claimed as new, and desired to be secured 20 by Letters Patent, is—

1. A railway-signal comprising an audible alarm mounted on a support near the road-bed, a shaft mounted in bearings between the rails, a spring surrounding and movable 25 bodily on said shaft, a trip-arm on said spring extending up within the path of the car-axles

and a flexible connection between said arm and the alarm, substantially as described.

2. A railway-signal comprising a gong, a hammer, a shaft mounted in bearings be- 30 tween the rails, a spring surrounding and bodily movable on said shaft, a trip-arm forming an integral extension of said spring and extending up within the path of the car-axles, and a flexible connection between the arm 35 and the hammer, substantially as described.

3. A railway-signal comprising a gong, a hammer, a shaft mounted between the rails and provided with a flaring mortise, a spring surrounding said shaft and having one end 40 movably fitted in said mortise so that the spring may shift bodily on the shaft, a trip-arm forming a continuation of said spring, and a flexible connection attached to said trip-arm and hammer. 45

In testimony whereof I have signed this specification in the presence of two subscribing witnesses.
